UNITED STATES PATENT OFFICE.

JOHN F. GAFFEY AND GEORGE W. COOK, OF NEW HAVEN, CONN.

RIFLE-SIGHT.

SPECIFICATION forming part of Letters Patent No. 290,225, dated December 18, 1882.

Application filed November 5, 1883. (No model.)

To all whom it may concern:

Be it known that we, JOHN F. GAFFEY and GEORGE W. COOK, citizens of the United States, residing at New Haven, in the county of New Haven and State of Connecticut, have invented certain new and useful Improvements in Rifle-Sights, of which the following is a specification, reference being had therein to the accompanying drawings, in which—

10 Figure 1 is a side elevation of our improved rifle-sight, in which a sectional view of the base is also given on line $x x$, Fig. 7. Fig. 2 is a face view of the improved rifle-sight complete. Fig. 3 is a perspective view of a portion of the sight-leaf, having the combination sight-block attached thereto. Fig. 9 represents the remaining portion of the sight-leaf in perspective, and was detached, as shown, to facilitate placing all the views upon one 20 sheet. Figs. 4, 5, 6, 7, 8, 10, and 11 are views of detailed parts, fully described hereinafter.

Letters of like name and kind refer to like parts in each of the drawings.

The design of our invention is to increase 25 the efficiency of the rifle-sight, and render more certain and accurate the operation of the mechanism in wind-gage sights; and to this end it consists of a rifle-sight in which the shaft upon which the sight-leaf operates is 30 adapted to be adjusted laterally with the longitudinal axis of the rifle-barrel, and securely fixed upon any point desired by suitable check-nuts.

It consists, further, in a rifle-sight having 35 a combination sight-block fixed upon the sight-leaf, and adapted to be moved in a vertical plane thereupon.

It consists, further, in a rifle-sight provided with graduations upon the combination sight-block and sight-leaf, operating in conjunction 40 to form both a vernier and ordinary sightscale.

It consists, finally, of the construction and arrangement of the parts, substantially as and for the purpose hereinafter shown and described.

In the annexed drawings, A represents a combination sight-block provided with a rectangular opening, upon the lower side of which is an "open-sight" notch, a , and directly 50 above this rectangular opening, in the center of the concave recess, said recess being made

in the block A, is a small aperture, b , to be used as a "peep-sight." This combination sight-block A has the form shown in Fig. 4, which gives an end and side elevation of the 55 sight-block, showing the shoulder d and projection e , the projection e being provided with a screw-thread, upon which the nut e is adapted to operate. The shoulder d is made to fit the slot in the leaf B, having a depth less than 60 the thickness of the said leaf, as shown by broken lines in Fig. 1, providing an open space between the block A and nut e when the nut is screwed against the leaf B, as in Fig. 1, thereby clamping the sight-block A at any desired 65 point on the leaf B. The leaf B is provided with a graduated scale upon one edge, the subdivisions of which, in connection with suitable graduations on the side of the sight-block A, arranged opposite the peep-sight b , operate as 70 a vernier-scale for the adjustment of the sight-block A when using the peep-sight b . A single line is placed opposite the notch a , which operates, in connection with the same subdivisions on leaf B, as an ordinary elevating scale. 75

Fig. 7 is a plan of the base-plate D, which is provided with two upright lugs, i and i' , each lug having a hole, h , which corresponds in diameter with the pin F. This base-plate D is properly recessed on the under side, to 80 permit the flat spring E being placed therein and have sufficient space to operate. The spring E is secured to the base-plate D by the screw y at one end, as in Fig. 1, while the other end, being free, is bent in an upward 85 curve, and is adapted to fit into the groove g .

Figs. 10 and 11 represent the two parts into which the pin F is divided. In Fig. 11 the size of the pin is reduced at r to correspond with the diameter of the hole m in the hub of 90 the leaf B, and serves as a journal, upon which the leaf B operates when being elevated for use. At s still another reduction in the size of the pin F is made, and provided with a suitable thread, to enable it being screwed 95 into the internally-threaded hole, n , Fig. 10, as shown. A screw-thread is placed upon each end of the pin F, upon which the check-nuts C and C' operate. o and o' are graduations on the pin F, by which the lateral adjustment of the leaf B is measured. When the parts are in the position shown in Fig. 2, it is 100

obvious that if it is desired to move the leaf B to the right, unscrewing the check-nut C and tightening up C' will cause the pin F to be moved longitudinally to the right, carrying the leaf B with it to the right. By a reversal of the operation the leaf B will be moved to the left, and this adjustment is measured by the graduation-lines o and o.

A great advantage gained by our improved sight is that whenever the leaf B is closed down upon the gun, which is invariably the case when the sight is not in use, and again elevated for use, no change of position of the leaf B and appurtenant sight-block A in relation to the line of sight upon which it was last adjusted is incurred, as the leaf B operates upon the smooth journal r, and the pin F is held firmly in position by the check-nuts C and C'.

We have shown in the drawings a sight which is adapted to being attached to the "wrist" or "grip" of the stock in the rear of the rifle-barrel, which requires the leaf B, when elevated for use, to stand at an angle of more than ninety degrees with the base-plate D. The difference in the vertical position of

the leaf B may be regulated by the position of the projection f on the lug i, against which the leaf B is firmly held, when elevated for use, by the peculiar end of the spring E interlocking in the groove g, as shown in Fig. 1.

Having described our invention, what we claim as new, and desire to secure by Letters Patent, is—

In a gun-sight, the combination of the movable sight-block A, having the open-sight notch a and peep-sight aperture b, with the slotted leaf B, provided with the elevating scale, as described, and the pin F, having the graduations o and o and adjusting check-nuts C and C', the pin F being adapted to a longitudinal movement through the lugs i and i on the base-plate D, together with the spring E, groove g, and projection f, all substantially as and for the purpose set forth.

In testimony whereof we affix our signatures in presence of two witnesses.

JOHN F. GAFFEY.
GEORGE W. COOK.
